CLAIM

The ornamental design for a massage brush, as shown and described.

DESCRIPTION

FIG. 1 is a front, top and right-side perspective view of a massage brush showing my new design assembled; FIG. 2 is a rear, bottom and left side perspective view thereof;

FIG. 3 is a perspective view thereof, shown disassembled; FIG. 4 is a front-view of FIG. 1;

FIG. 5 is a rear view thereof;

FIG. 6 is a left side view thereof;

FIG. 7 is a right side view thereof;

FIG. 8 is a top plan view thereof;

FIG. 9 is a bottom plan view thereof; and,

FIG. 10 is an enlarged view of portion "10" shown in FIG. 1.

The dash-dash broken lines shown in the drawings depict portions of the massage brush, and form no part of the
